UNITED STATES PATENT OFFICE.

EDWARD Y. MOORE, OF CLEVELAND, OHIO.

HOIST.

946,253.

Specification of Letters Patent. Patented Jan. 11, 1910.

Application filed June 9, 1906. Serial No. 320,932.

To all whom it may concern:

Be it known that I, EDWARD Y. MOORE, a citizen of the United States, residing at Cleveland, in the county of Cuyahoga and State of Ohio, have invented a certain new and useful Improvement in Hoists, of which the following is a full, clear, and exact description, reference being had to the accompanying drawings.

10. My prior patent No. 757,333 granted April 12, 1904, shows and claims a hoist wherein the raising is accomplished by a yoke with internal teeth surrounding an external gear connected with the main pulley, 15 a pair of rotatable eccentrics serving to gyrate the yoke.

The present invention is an improvement on the one just referred to and is designed to increase the efficiency of such a hoist. It 20 is characterized by the employment of a plurality of gyrating yokes with internal teeth so arranged as to balance each other, reducing the friction on the bearings and thereby increasing the efficiency of the hoist, 25 as well as its life.

The invention is hereinafter more fully described and its essential characteristics set out in the claims.

The drawings show my improved hoist 30 embodied in an apparatus suspensible from a hook having a hand chain wheel.

Figure 1 is a vertical cross section of the hoist; Fig. 2 is a side elevation thereof with the cover for the gears removed; Fig. 3 is a 35 plan partially in section; Fig. 4 is a sectional elevation taken just inside the left-hand frame member of Fig. 1, showing the two yokes in place, but omitting the gear-teeth on the inner yoke, for clearness; Fig. 5 is a similar view with the left hand yoke removed; Fig. 6 is a horizontal section through 40 one of the double driving eccentrics, as indicated by the line 6-6 of Fig. 4; and Fig. 7 is a perspective, illustrating the double eccentric.

The frame of the hoist, as shown, consists of two side members A and A' bolted together at their upper ends and embracing a hook C swiveled between them. Between 45 the side members of the frame is the raising chain pulley or main-pulley D. This pulley is rotatably carried by the frame members, the supporting means shown being a stationary hollow sleeve G, which extends from one frame member to the other and constitutes virtually a portion of the frame. The

main shaft F, of the hoist extends through the sleeve G, and carries at one end a pinion H, which meshes with a pair of gears J and J', which gears are connected with gyrating 60 mechanism adapted to engage an external gear d, forming an extension of the main pulley D. A suitable plate A² is shown as covering the gears, being secured to a flange a on the frame member A.

The description given in the above paragraph responds to the hoist shown in my patent referred to. In that patent, however, the gyrating mechanism connecting the gears J and J' with the external gear d consists of a single yoke and two eccentrics, one connected with the gear J and the other with the gear J'. In the present invention I provide a plurality of yokes side by side, two (E and E') being shown in the drawings. 70 These yokes are mounted on the two multiple eccentrics K and K', connected with the gears J and J' respectively.

When two yokes are employed, each eccentric is formed double as shown in Figs. 80 6 and 7, and comprises two eccentric portions k and k', located in parallel planes and extending in diametrically opposite directions. These eccentric portions have the same axis, which is the axis of the extensions k² and k³ of the double eccentric, which extensions form the journals, whereby the double eccentric is rotatably mounted in the frame members A and A'. The extension k³ furthermore provides means for securing the 90 gear J, or J' which is keyed on such eccentric and further held by the jam nut j. Between the two portions k and k' of the double eccentric is a flange portion k⁴ which forms a washer between the yokes E and E'. The double eccentric member described is 95 preferably made of a single piece of metal. Surrounding the periphery eccentrics k and k' are a series of rollers L which reduce the friction with the yokes. The outer ends of these rollers are guided by the frame members and the inner ends by the flange k⁴.

From what has been described it will be apparent that when the shaft F is rotated the two double eccentrics are simultaneously rotated causing the two yokes E and E' to gyrate. The external gear d, and hence the main pulley D, are thus caused to rotate at a speed slower than the speed of rotation of the shaft F. Each gyration of the yokes gives the external gears d a small portion of the rotation depending on the difference be-

tween the number of teeth on the external gear and the yoke.

Where but one yoke is employed a raising

5 force equal to the weight of the load becomes applied to the gear d , and when this raising

force is acting downward the thrust on the main bearings is substantially twice the load.

By dividing the yoke in two and providing each eccentric device with two portions ex-

10 tending in opposite directions, one yoke is acting upward on the gear d while the other is acting downward. The thrust on the bear-

ings caused by this lifting force therefore counterbalances itself, reducing the friction

15 on the bearing by approximately as much as 50% in some portions of the rotation. Likewise the lateral thrust on the eccentrics

counterbalances itself, because when one yoke is pulling in one direction and the other

20 is pulling in the other, the downward thrust on the eccentric bearings is correspondingly reduced. The aggregate reduction in friction

25 causes a very considerable increase in efficiency of the hoist. Moreover, the raising

action is much smoother. My prior patent referred to shows a spring, helping support the weight of yoke and reducing the jerking.

The present invention is more efficient and saves the expense of the spring. The reduc-

30 tion in the thrust on the various bearings also increases the life of the hoist. Thus the present improvement introduces three ad-

35 vantages: increased efficiency, smoother operation and longer life.

35. The hand chain wheel is shown as mounted on the shaft A and connected with it through a friction brake which operates to prevent the load running down. This brake

40 is shown and claimed in Patent No. 794,997 granted to me July 18, 1905. Briefly de-

scribed, it includes a metal cup Q, loosely journaled on a collar P, on the shaft. The cup has ratchet teeth on its exterior with

45 which meshes a pawl Y carried by the frame, the ratchet teeth being in such direction that

they may click idly under the pawl when the load is raised.

S indicates friction disks which are alter-

50 nately secured to the collar P and to the cup Q. Outside of the disks is a pressure

plate T, against which bears the hand chain wheel N. This wheel has an inclined sur-

face n, coöoperating with an incline w, on a collar W, rigid on the shaft. The result of

55 this is that when the hand chain wheel is turned in the direction to cause the incline n to ride up on the incline w, the hand chain

wheel is forced inward, clamping the disks, and the cup and disks rotate as a whole with

60 the shaft and hand chain wheel. When the elevating ceases, the clamped brake holds the cup rigid with the shaft, and the pawl

thus holds the load against descending. To

65 lower the load, the hand chain wheel is turned backward allowing it to move away

from the clamping plate T, relieving the disks and allowing the load to descend. During such descent the pull on the hand chain wheel keeps it in advance of the de-
scending load.

70 I claim:

1. In a hoist, the combination of two eccentrics rigid with each other, a gear rigid with said eccentrics, a meshing driving gear, two gyrating members operated by said 75 eccentrics, and raising mechanism operated by said gyrating members.

2. In a hoist, the combination of an external gear, a plurality of yokes located side by side and having internal teeth engaging 80 said gear at different points, and mechanism geared together for gyrating said yokes.

3. In a hoist, the combination of an external gear, a plurality of yokes having internal teeth engaging said gear at different 85 points, and two driving members geared together and each having a plurality of eccen-

trics for gyrating said yokes.

4. In a hoist, the combination of a driving gear, a shaft having two eccentrics, a 90 gear on said shaft connecting with the gear first mentioned, two gyrating members operated by said eccentrics, and raising mechanism operated by said gyrating members.

5. In a hoist, the combination of an external gear, members placed side by side and surrounding the external gear and having internal gear teeth adapted to simultaneously mesh with the external gear at dif-
95 ferent points respectively, two driving de-

vices, both coöperating with each member for gyrating them in orbits which are similar but differently located, and mechanism connecting said driving devices and insuring their simultaneous operation.

6. In a hoist, the combination of an external gear, two yokes placed side by side and surrounding the external gear and having internal gear teeth adapted to mesh with opposite sides of the external gear respec-
100 tively, a pair of double eccentrics each having two eccentric portions which extend in opposite directions and are adapted to drive and guide said yokes and gearing connect-
105 ing the two eccentrics.

7. In a hoist, the combination of a pulley, mechanism for rotating it, including a plurality of gyrating members, eccentric mechanism for gyrating said members, said mechanism comprising eccentrics extending from 110 the same axis in different directions, one eccentric for each member, and a flange be-
tween the eccentrics serving to separate the members.

8. In a hoist, the combination of an external gear, yokes surrounding the same side by side and having internal gear teeth engaging different portions of the external gear, an eccentric member for gyrating the yokes, said member comprising eccentrics 115

120

125

130

- extending from a common axis in different directions, one eccentric for each yoke, and a flange between the eccentrics serving to separate the yokes.
5. In a hoist, the combination of a frame, a pair of eccentric members journaled therein, each eccentric member comprising two eccentrics extending in opposite directions with a flange between them, two rollers rolling between the peripheries of the 60 eccentrics and the openings in the yoke.
10. In a hoist, the combination of a pulley, internal and external meshing gearing for driving the same, one portion of such gearing comprising a plurality of members, a 65 plurality of separated eccentrics for driving said members, and gearing connecting said eccentrics together.
15. In a hoist, the combination of a pulley, a gear connected therewith, a plurality of 70 geared members meshing with said gear, a plurality of eccentrics each adapted to operate with said plurality of members, and gearing connecting said eccentrics, whereby they operate in unison. 75
20. In a hoist, the combination of a pulley, an external gear connected therewith, a plurality of internal gears surrounding the external gear, a plurality of eccentrics, each adapted to operate with all of said internal gears, and 80 gearing connecting said eccentrics.
25. In a hoist, the combination of a pulley, an external gear connected therewith, two internal gears surrounding the external gear, two sets of eccentrics, each set co-operating 85 with both internal gears, and gearing connecting the two sets of eccentrics.
30. In a hoist, the combination of a pulley, a gear connected therewith, a plurality of yokes surrounding the gear and having 90 teeth engaging it at different points, a pair of eccentric members each comprising as many eccentrics as there are yokes, which eccentrics extend in different directions, and gearing connecting the two eccentrics, where- 95 by they operate in unison.
35. In a hoist, the combination of an external gear, a plurality of yokes having inwardly projecting teeth and surrounding said external gear, driving mechanisms en- 100 gaging the yokes at two points for alternately moving said yokes, and movable mechanism connecting said driving mechanisms and insuring their simultaneous operation.
40. In a hoist, the combination of a pulley, a gear connected therewith, a pair of driving eccentrics, means operated by the eccen- 105 trics for rotating the said gear, said means being arranged to balance itself without the employment of a spring, and gearing connecting the eccentrics.
45. In a hoist, the combination of a pulley, a gear connected therewith, a pair of driving eccentrics, means operated by the eccen- 110 trics for rotating the said gear, said means being arranged to balance itself without the employment of a spring, and gearing connecting the eccentrics.
50. In a hoist, the combination of a frame comprising a pair of side plates brought together near their tops and a hook swiveled in said plates at their junction, a pulley carried by the frame beneath the hook, a gear on said pulley, a plurality of yokes surrounding the pulley, a pair of eccentrics operating in openings in both yokes, and
55. In a hoist, the combination of a frame 115 comprising a pair of side plates brought together near their tops and a hook swiveled in said plates at their junction, a pulley carried by the frame beneath the hook, a gear on said pulley, a plurality of yokes surrounding the pulley, a pair of eccentrics operating in openings in both yokes, and
60. In a hoist, the combination of a pulley, an external gear connected therewith, a plurality of internal gears surrounding the external gear, a plurality of eccentrics, each adapted to operate with all of said internal gears, and 120 gearing connecting said eccentrics.
65. In a hoist, the combination of a pulley, an external gear connected therewith, two internal gears surrounding the external gear, two sets of eccentrics, each set co-operating with both internal gears, and gearing connecting the two sets of eccentrics.
70. In a hoist, the combination of a pulley, a gear connected therewith, a plurality of yokes surrounding the gear and having 125 teeth engaging it at different points, a pair of eccentric members each comprising as many eccentrics as there are yokes, which eccentrics extend in different directions, and gearing connecting the two eccentrics, where- by they operate in unison.
75. In a hoist, the combination of a pulley, an external gear connected therewith, a plurality of yokes surrounding the gear and extending onto each side thereof, a plurality 130 of eccentric members engaging the yokes on different sides of the gear, two mechanisms for driving said eccentric members and gearing connecting said two mechanisms.
80. In a hoist, the combination of a pulley, an external gear connected therewith, two internally 135 geared yokes surrounding the external gear, two eccentric members for driving the yokes, each member having a plurality of eccen- trics, a gear on each eccentric member, and a driving gear meshing with said gears.
85. In testimony whereof, I hereunto affix my signature in the presence of two witnesses.
